UNITED STATES PATENT OFFICE.

ELBERT W. BARTON, OF BINGHAMTON, NEW YORK.

TURBINE.

1,263,511.

Specification of Letters Patent. Patented Apr. 23, 1918.

Application filed June 27, 1916. Serial No. 106,241.

To all whom it may concern:

Whereas I, ELBERT W. BARTON, a citizen of the United States, and residing at Binghamton, in the county of Broome and State 5 of New York, have invented a certain new and useful Improvement in Turbines, of which the following is a specification.

My present invention relates to turbines and more particularly to such embodying 10 two coöperating peripherally confronting rotors, the one rotor provided with recesses which are complementary to recesses of the other rotor to provide pockets for the jet or jets of fluid under pressure.

15 The principal objects of my invention are to provide turbines, each embodying two rotors which may be the product of the same mold or in other words, complementary, thus reducing the cost of manufacture, and facilitating assembling and replacing of a 20 broken or worn rotor; to provide turbines each embodying two rotors, and each rotor embodying a peripheral flange to extend laterally of the recesses of its coacting rotor 25 and closing the said recesses laterally prior to and during the entry of the jet into the pockets thus formed by coacting recesses, but which render the said recesses open laterally after the impact of the jet against its 30 walls, thus relieving back pressure by freely giving up the fluid from the turbine rotors after it has served its purpose as an impelling means.

Other objects of my invention will appear 35 in the following detailed description, taken in connection with the accompanying drawings, forming a part of this specification, and in which drawings:

Figure 1 is a view partly in elevation and 40 partly in central vertical section through a turbine constructed according to my invention.

Fig. 2 is a central horizontal sectional view through the same.

45 Fig. 3 is a central vertical transverse sectional view through fluid-conducting and controlling means, showing parts of the turbine in operative relation thereto, in side elevation.

50 Fig. 4 is a fragmentary perspective view of one of the rotors.

Fig. 5 is a perspective view of a casing forming a part of the fluid-conducting means.

55 In the drawings, where similar characters refer to similar parts throughout the several

views, A designates a casing provided with an ingress opening B and an egress opening C for the fluid; D rotors in said casing, carried by shafts E and F; G fluid-conducting 60 means; and, H fluid-controlling means.

Referring first to the rotors D, arranged within the casing A so as to peripherally confront one another, they are formed to provide a plurality of peripheral recesses 6, 65 each rotor being provided with a flange 7 extending laterally at one face of the rotor, closing said recesses laterally, said flange extending beyond said recesses a distance greater than the depth of the pockets, for a 70 purpose to be subsequently set forth. The recesses 6 are open laterally of the rotor at its face opposite to flange 7 and may be provided with a circumferential groove 9 at said face, as clearly shown in Fig. 4 of the drawings. 75

The recesses 6 may be of any shape, but it is preferred to form them with a relatively flat radially disposed wall and an arcuate wall 12 leading outwardly from the base of 80 wall 10 to a point adjacent the outer end of the next adjacent wall 10, as is clearly shown in Fig. 1 of the drawings.

The rotors are so arranged on their respective shafts E and F, supported by bearings 13 that the flange 7 of one rotor extends laterally of the adjacent recess 6 of the other rotor closing the same as the said recesses approach one another for the provision of a pocket as is obvious from an inspection of 90 Fig. 2 of the drawing. These flanges may extend, if desired, into the said grooves 9 so as to seal the recesses 6 as the coacting recesses align at the plane common to the axes of rotation of the rotors D. 95

Referring now to the fluid-conducting means, in the example shown, it may comprise a pipe or conduit 14; a casing 15 extending through the ingress opening B of casing A; nozzles 16 at that portion of casing 15 within the casing A, and directed toward the coacting recesses 6; valve-controlled drain pipe 17 and a conduit 18, the latter of which may be in communication with a safety valve 20 from which leads a 105 pipe 21 for the purpose of conducting any fluid which is released through safety valve 20. If desired, a gage 22 may be placed in communication with the conduit 14 for determining the fluid pressure, and the usual 110 control valve 23 is shown disposed in operative relation to conduit 14.

The means H, in the example shown, comprises three sets of mechanisms,—an automatic speed control 24, a manually-operated control valve 25; and mechanism 26 for moving the casing 15 toward or from the rotors D. Referring first to the mechanism 24, it may comprise a governor 27 operated from shaft F, and through meshing bevel gears 28 and 29, the latter of which is rigid with 10 an upright shaft 30 on which governor 27 is mounted; and, a valve 31 adapted to be moved toward or from a seat 32 in casing 15, as by having valve stem 33 operatively connected with a lever 34 actuated by governor 27 as through collar 35, the lever 34 being pivoted as at 36. Thus, as the turbine speeds up the governor 27 is actuated, imparting movement to lever 34 and reciprocating valve 31 according to the speed. 20 The valve 25 may be of any suitable type, disposed in casing 15 and adapted to be actuated as by handle 37 exteriorly of casing 15.

As to the mechanism 26, it may comprise 25 bolts 38 having engaging portions 39 said bolts having screw-threaded engagement with abutments 40 on the conduits 14 and 18, and abutments 41 mounted on the upper portion of casing A. The conduits 14 and 30 18 may be of flexible material, or may be arranged in connection with the drain pipe 17 in such a manner as to be oscillatable with respect thereto, and by rotating the bolts 39, the abutments 40 and 41 may be moved away 35 from one another, or toward one another, actuating the casing 15 accordingly.

The casing 15 may be provided with 40 arcuate grooves 42 within the casing A, said grooves to accommodate the flanges 7 and for the purpose of providing fluid-tight engagement of portions of the turbine to prevent the escape of fluid, under pressure, about the casing 15. The said casing is also formed with arcuate walls 43 adjacent the 45 rotors, and unions 44 may be provided in the conduits 14 and 18 to facilitate detachment of the casing 15 from operative relation to the turbine for the purpose of repair or to enable said casing to be cleaned.

50 The operation of the turbine is as follows: Assuming that fluid, under pressure, is introduced into the casing A, through nozzle 16, the said fluid impinges upon the walls of recesses 6, of rotors D as they are 55 approaching the plane common to the axes of rotation of said rotors, and as the said recesses are approaching one another to form pockets, at which time the flanges 7 co-operate with the recesses of adjacent rotors to 60 seal the said recesses 6 laterally. As the recesses 6 pass the said plane they are moved away one from another permitting the fluid to escape from operative relation to the rotors. It is to be observed that the fluid 65 may escape not only from the peripheral

portion of the rotors but may find egress laterally of each rotor at the face thereof, opposite to flange 7.

The rotors D may be the product of the same mold inasmuch as they are complementary, and when disposed with their peripheries confronting one another, and with the flange of one rotor fitting into the groove 9 of the other rotor or to lie laterally of the adjacent recesses 6, a plurality of substantially air-tight pockets are formed intermediate the rotors and against the walls of which the impelling fluid impinges. 70

Changes in details may be made without departing from the spirit or scope of my invention; but, 80

I claim;

1. In a turbine, the combination of two peripherally confronting rotors, each rotor provided with a plurality of circumferentially disposed recesses open laterally at its one side and a flange closing said recesses laterally at the other side of the rotor, said rotors arranged with the flange of one closing the recesses of the other rotor laterally, 85 when disposed adjacent thereto, and the flange of said last-mentioned rotor closing the recesses of said first-mentioned rotor laterally when adjacent thereto.

2. In a turbine, the combination of two 90 peripherally confronting rotors, each rotor provided with a plurality of circumferentially disposed recesses open laterally at its one side, said recesses complementary to provide a pocket as they cross the plane common to the axes of rotation of said rotors, 95 and a wall for each recess closing the same laterally at one side of the rotor and extending laterally of the open side of the coacting recess. 100

3. A turbine comprising in combination, 105 a casing, two peripherally confronting rotors within said casing, each rotor provided with a plurality of circumferentially disposed recesses open laterally at its one side, and a flange closing said recesses laterally at the other side of the rotor, said rotors arranged with the flange of one rotor closing the recesses of the other rotor laterally when disposed adjacent thereto, and the flange of said last-mentioned rotor closing recesses of said first-mentioned rotor laterally when adjacent thereto, and means for introducing fluid under pressure intermediate said rotors to impinge the walls of said recesses thereof. 110

4. A turbine comprising in combination, a casing, two peripherally confronting rotors within said casing, each rotor provided with a plurality of circumferentially disposed recesses open laterally at its one side, and a flange closing said recesses laterally at the other side of the rotor, said rotors arranged with the flange of one rotor closing the recesses of the other rotor laterally when disposed adjacent thereto, the flange of said 115 120 125 130

last-mentioned rotor closing recesses of said first-mentioned rotor laterally when adjacent thereto, means for introducing fluid under pressure intermediate said rotors to 5 impinge the walls of said recesses thereof, and mechanism for moving said means toward or from said rotors.

5. A turbine comprising in combination, a casing, two peripherally confronting rotors within said casing, each rotor provided with a plurality of circumferentially disposed recesses open laterally at its one side, said recesses complementary to provide a pocket as they cross the plane common to 10 the axes of rotation of said rotors, and a wall for each recess closing the same laterally at one side of the rotor and extending laterally of the open side of the coacting recess, and means for introducing fluid under 15 pressure intermediate said rotors to impinge the walls of the said recesses thereof.

6. A turbine comprising in combination, a casing, two peripherally confronting rotors within said casing, each rotor provided with a plurality of circumferentially disposed recesses open laterally at its one side, said recesses complementary to provide a pocket as they cross the plane common to 20 the axes of rotation of said rotors, and a wall for each recess closing the same laterally at one side of the rotor and extending laterally of the open side of the coacting recess, means for introducing fluid under pressure intermediate said rotors to impinge 25 the walls of the said recesses thereof, and mechanism for moving said means toward or from said rotors.

7. A turbine comprising in combination, a casing, two peripherally confronting rotors within said casing, each rotor provided with a plurality of circumferentially disposed recesses open laterally at its one side 30

and a flange closing said recesses laterally at the other side of the rotor, said rotors arranged with the flange of one rotor closing recesses of the other rotor laterally when disposed adjacent thereto, and the flange of said last-mentioned rotor closing recesses of said first-mentioned rotor laterally when adjacent thereto, and a casing 35 fitting between the said flanges of said rotors and provided with a nozzle and directed toward the said recesses thereof.

8. A turbine comprising in combination, a casing, two peripherally confronting rotors within said casing, each rotor provided with a plurality of circumferentially disposed recesses open laterally at its one side and a flange closing said recesses laterally at the other side of the rotor, said rotors 40 arranged with the flange of one rotor closing recesses of the other rotor laterally when disposed adjacent thereto, and the flange of said last-mentioned rotor closing recesses of said first-mentioned rotor laterally when adjacent thereto, a casing fitting 45 between the said flanges of said rotors and provided with a nozzle and directed toward the said recesses thereof, and mechanism for moving said casing toward or 50 from said rotors.

9. As an article of manufacture, a turbine rotor provided with circumferentially disposed recesses open at the periphery and one face of the rotor, a peripheral flange 55 closing the said recesses at the other face of the rotor, said flange extending beyond said recesses a distance greater than the depth of said recesses, and a circumferential groove at the face of the rotor opposite 60 to said flange, said groove open to the periphery of the rotor.
